CLAIM

I claim the ornamental design for a hearing assistance device, as shown and described.

DESCRIPTION

FIG. 1 is a perspective view of a hearing assistance device of the present invention,

FIG. 2 is a front elevation view of the hearing assistance device of FIG. 1;

FIG. 3 is a back elevation view of the hearing assistance device of FIG. 1;

FIG. 4 is a left side elevation view of the hearing assistance device of FIG. 1;

FIG. 5 is a right side elevation view of the hearing assistance device of FIG. 1;

FIG. 6 is a top plan view of the hearing assistance device of FIG. 1; and,

FIG. 7 is a bottom plan view of the hearing assistance device of FIG. 1.

The broken lines in FIGS. 2-6 are included for the purpose of illustrating portions of the hearing assistance device that form no part of the claimed design.
